Term of patent 14 years

(Cl. D91—3)

FIGURE 1 is a top plan view of a refilling valve for animal water troughs, toilet flush tanks and similar use showing my new design;

FIGURE 2 is a side elevation thereof;

FIGURE 3 is a bottom plan view thereof;

FIGURES 4 and 5 are end elevations thereof as seen from opposite ends, respectively, of FIGURE 2; and

FIGURE 6 is a fragmentary view of the opposite side of FIGURE 2 as viewed along the line 6—6 in FIGURE 5.

I claim:

The ornamental design for a refilling valve for animal water troughs, toilet flush tanks and similar use, as shown.
